UNITED STATES PATENT OFFICE.

THOMAS E. MILLES, OF PITTSBURGH, PENNSYLVANIA.

COPY-HOLDER.

1,286,053.

Specification of Letters Patent. Patented Nov. 26, 1918.

Application filed June 20, 1917. Serial No. 175,886.

To all whom it may concern:

Be it known that I, THOMAS E. MILLES, a citizen of the United States, residing at Pittsburgh, in the county of Allegheny and State of Pennsylvania, have invented new and useful Improvements in Copy-Holders, of which the following is a specification.

This invention relates to a copy holder, the primary object of which is to hold various kinds of copy directly in front of the operator and in which the parts are so constructed and associated as to provide a positive feed of the copy, causing each line to appear in consecutive order above an indicator.

An object of the invention is to provide a copy holder capable of supporting a heavy bound book as well as one or more sheets or a stenographer's notebook.

20 Besides the above my invention is distinguished in the manner of associating the parts so that the same may be readily folded and capable of moving down with the typewriter when the typewriter desk is closed.

25 With these and other objects in view the invention will be better understood from the following detail description taken in connection with the accompanying drawings wherein:—

30 Figure 1 is a front elevation of the device with the curtains removed.

Fig. 2 is an enlarged view of the base portion.

Fig. 3 is a cross sectional view.

35 Fig. 4 is a horizontal sectional view.

Figs. 5 and 6 are sectional views through the feed mechanism.

Figs. 7 and 8 are detail views of the connecting plate.

40 Figs. 9 and 10 are detail views illustrating the use of the book support and brackets.

Figs. 11 and 12 are detail views of the regulator.

45 Figs. 13, 14 and 15 are detail views of the marker.

Fig. 16 is a perspective view of the clip.

Fig. 17 is a detailed view. Fig. 18 is a diagrammatic view illustrating the manner in which the flexible bands are connected to 50 the rollers.

Again referring to the drawings the numeral 1 designates a base including ears 2, to which are pivotally connected certain links of a group of pivotally connected links 3 forming a frame F, that may be extended

or contracted. Other of the links support shafts 4 upon which are journaled rollers 5 that in turn move upon tracks 6 carried by the base. These shafts 4 also have mounted thereon spools 7 while a third spool 8 is 60 journaled on a shaft 9 supported in the ears 2 and which forms the pivot for the adjacent links of the frame.

Connected to the spools 7 are flexible elements in the form of steel bands 10 passing 65 to, and wrapped around the drum 11 that forms one element of the feed mechanism 12 mounted in the house 13. One of the bands passes around the spool 8 before being connected to the spool 7, with the result that 70 pull upon both bands will move the rollers toward each other for the purpose of extending the frame, and vice versa when the bands are released. When pressure upon the bands is removed and the frame is collapsed the 75 shock created thereby is absorbed by the spring 14, passed under the spool 8 and connected to the spools 7. The movement of the frame toward its intermediate collapsed position is limited by the stop device 15 shown 80 in this particular instance as consisting of a strip 16 having a central portion riveted to the base as illustrated at 17 while its end portions are arranged to form shoes 18 adapted to engage the spools 7 when the 85 shoes are moved into the path of movement of the spools by the trip 19. The resiliency of the strip 16 tends to move the shoes out of the path of movement of the spools so that the frame may be finally collapsed such 90 as when the typewriter desk is to be closed.

This trip device 19 consists of a manually operated rod 20 pivotally connected to arms 21 that are in turn pivotally connected to the shoes in such a manner that when the arms 95 21 are in operative position they will lie in alinement with the direction of travel of the shoes when assuming an inactive position. It is of course to be understood that other devices may be used for limiting the movement of the rollers and the construction illustrated is only shown in a diagrammatic manner.

The upper portion of the frame F has certain of its links pivotally connected to a 105 supporting member 22 while other links support rollers 23 that bear upon the under surface of the member 22 so as to reduce friction and distribute the thrust of the frame. This member 22 supports a clamp 110

24 resiliently held in engagement with the member 22 by the resilient tongues 25 engaging an extension 26 on the clamp 24. This clamp 24 is used when the holder supports sheets or other thin articles while brackets 27 are provided for supporting books or other relatively thick articles. These brackets are substantially Z-shaped formation with one end portion embracing the 10 member 22 while the other end portion is arranged to engage the book.

Also supported by the base is a marker 28 consisting of pivotally connected arms 29 directly pivoted to the base, with the result 15 that the marker may be folded in a compact position. The arms 29 support a rod 30 upon which is swingingly mounted a pair of strips or plates 31 with the result that one plate may swing independent of the other 20 so as to compensate for the difference in thickness of a book when unfolded, that is to say, should the number of pages in one portion of the book when open, be greater than the other portion, the plates 31 compensate for the difference in thickness. Of 25 course it is to be understood that when this takes place the clip 32 hereinafter described will be removed.

When the marker is used upon flat work 30 such as flat sheets the strips 31 are fixed relative to each other by a clip 32 engaging both strips. A suitably located spring 33 may be used to hold the marker in engagement with the sheet and to facilitate this 35 action the arms are constructed to have a locking engagement with each other and the base as illustrated at 34 in Figs. 13, 14 and 15.

In Figs. 5 and 6 I have illustrated one 40 form of feed mechanism for driving the drum 11 which consists of a manually operated lever 35 pivotally connected to the base as illustrated at 36 with its short arm connected to a dog 37 acting upon the 45 ratchet 38 secured to the drum 11. This ratchet is held against backward movement by a pawl 39 that has an extension 40 arranged to be engaged by the finger 41 on the lever when the latter has been thrown to its 50 extreme position in one direction with the result that the pawl 39 is released from the ratchet for allowing free movement of the drum.

A spring 42 is arranged to return the lever 35 to its normal position after each operation.

From the foregoing description it will be seen that upon manipulating the lever 35 the drum 11 will be rotated for taking up 60 the flexible elements 10 which owing to the connection with the spools move the rollers toward each other. Movement of the rollers toward each other causes the frame F to be extended and as the drum is moved step by step, the frame will be extended step by step,

the distance of each step corresponding to the spacing of the lines of printed matter. When it is necessary to collapse the frame to its original position it is only necessary to move the lever 35 to one of its extreme 70 positions which causes the finger 41 to depress the pawl 39 and allow the drum 11 free movement. The weight of the frame will cause the same to collapse to its original position which is reached when the 75 spools 7 engage the shoe 18. When it is necessary to fully collapse the frame the trip device 19 is operated which allows the shoes 18 to move out of engagement with the spools 7 and allows greater travel of the 80 rollers.

To complete the invention I provide a regulating device 43 for regulating the distance of travel of the lever 35 so that different spaces may be accommodated. In this 85 particular instance the regulating device consists of an adjustable stop 44 arranged in the path of movement of the lever and having screw threaded engagement with an indicator 45 slidably mounted in the slot 46 90 in the base and co-operating with a scale 47. If found advantageous in practice a curtain 48 may be provided for covering the frame and this curtain has one end wrapped around a spring roller 49 while the other 95 end is secured to the member 22 as indicated at 50.

It is to be understood that while all of the several features of my improved copy holder have special co-operation with one another and together constitute a particularly effective mechanism for the purpose in view, certain of these features may be applied in other relations, and I therefore desire to cover the combinations present in the several parts of my improved copy holder whether employed in the general organization shown or elsewhere.

It is further to be understood that the structural embodiment of the invention as 110 a whole and its various features as shown is merely illustrative and not restrictive since I am well aware that many of the details of construction can be widely varied without departing from the spirit of the 115 invention. I therefore do not desire to be limited in these particulars or in any others, except as set forth in the appended claims.

What I claim is:—

1. A copy holder comprising a base, an 120 extensible frame connected to the base, a foldable marker connected to the base and manually operated means for extending said frame including wheels supporting portions of the frame.

2. In a copy holder, an extensible frame consisting of a series of links pivoted together and certain of which being pivotally connected to a stationary support, rollers carried by certain of the remaining links 130

and manually operated means for moving the rollers toward and away from each other.

3. In a copy holder, an extensible frame consisting of a series of links pivoted together and certain of which being pivotally connected to a stationary support, rollers carried by certain of the remaining links and manually operated means for moving the rollers toward and away from each other, and a curtain supported by, and adapted to cover said frame.

4. In a copy holder, a base, a track formed upon the base, rollers mounted for movements on the track, an extensible frame consisting of links pivotally connected together and to the rollers and base, and means for moving the rollers toward and away from each other.

5. In a copy holder, a base, a track formed upon the base, rollers mounted for movements on the track, an extensible frame consisting of links pivotally connected together and to the rollers and base, and ratchet mechanism for moving the rollers toward and away from each other.

6. In a copy holder, a base, a track formed upon the base, rollers mounted for movements on the track, an extensible frame, consisting of links pivotally connected together and to the rollers and base, and flexible elements connected to the rollers and ratchet means for winding and unwinding said elements.

7. In a copy holder, a base, a track formed upon the base, rollers mounted for move-

ments on the track, an extensible frame consisting of links pivotally connected together and to the rollers and base, and flexible elements connected to the rollers, ratchet means for winding and unwinding said elements and a manually operated device for limiting the movement of the rollers.

8. In a copy holder, a base, rollers mounted for movement thereon, a link pivotally connected to the base and rollers, a drum, manually controlled means for operating the drum and a connection between the drum and rollers whereby the same may be moved toward and away from each other.

9. In a copy holder, a base, rollers mounted for movement thereon, a link pivotally connected to the base and rollers, a drum, manually controlled means for operating the drum and a connection between the drum and rollers whereby the same may be moved toward and away from each other, and a device for limiting the movements of the rollers.

10. In a copy holder, a base, rollers mounted for movement thereon, a link pivotally connected to the base and rollers, a drum, manually controlled means for operating the drum and a connection between the drum and rollers whereby the same may be moved toward and away from each other, and a device for limiting the movements of the rollers, and a shock coöperating with the rollers.

In testimony whereof I affix my signature.

THOMAS E. MILLES.
